(57) **CLAIM**

The ornamental design for a tweezer, as shown and described.

DESCRIPTION

FIG. 1 is a perspective view of a tweezer showing my new design.

FIG. 2 is a front view of a tweezer.

FIG. 3 is a rear view of a tweezer.

FIG. 4 is a left side view of a tweezer.

FIG. 5 is a right side view of a tweezer.

FIG. 6 is a top view of a tweezer; and,

FIG. 7 is a bottom view of a tweezer.

Any shading and cross-hatching are not features of the design but are utilized to illustrate the surface contours of the tweezer design in the drawings.

1 Claim, 7 Drawing Sheets
